(57) **CLAIM**

The ornamental design for a headgear for head-mounted display, as shown and described.

DESCRIPTION

FIG. 1 is a front perspective view of headgear for head-mounted display showing a first embodiment of our new design;

FIG. 2 is a front perspective view thereof in isolation without the display;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a rear perspective view thereof;

FIG. 10 is a front perspective view of headgear for head-mounted display showing a second embodiment of our new design;

FIG. 11 is a front perspective view thereof in isolation without the sample display;

FIG. 12 is a front view thereof;

FIG. 13 is a rear view thereof;

FIG. 14 is a top view thereof;

FIG. 15 is a bottom view thereof;

FIG. 16 is a left side view thereof;

FIG. 17 is a right side view thereof; and,

FIG. 18 is a rear perspective view thereof.

The broken lines represent environmental structure or unclaimed portions of the headgear for head-mounted display thereof and do not form a portion of the claimed design. In FIGS. 1–9, the use of line shading (e.g., for the plastic headgear connectors/clips) and textile hatching (e.g., for the straps) is intended to denote a difference in appearance/materials.
